UNITED STATES PATENT OFFICE.

MARIUS A. BAUER, OF WORCESTER, MASSACHUSETTS, ASSIGNOR TO M. J. WHITTALL ASSOCIATES, A VOLUNTARY ASSOCIATION OF MASSACHUSETTS.

ACTUATING AND SUPPORTING MECHANISM FOR THE KNOTTING TABLES OF ORIENTAL-RUG LOOMS.

Application filed May 18, 1927. Serial No. 192,446.

This invention relates to a loom for weaving oriental rugs or carpets and more particularly to a loom of the general type shown in Renard Patent No. 894,287. In such looms, a plurality of knotting devices are assembled on a knotting table, which is mounted for oscillating movement forward and rearward in the loom and also for rocking movement about an axis parallel to the lay. In such looms as previously manufactured, the mechanism for supporting and actuating the knotting table has been extremely complicated and expensive and has occupied a very objectionable location above the woven fabric throughout the width of the loom.

It is the general object of my invention to improve the supporting and actuating mechanism for the knotting table, simplifying the same and changing the location thereof so that the woven fabric will not be exposed to injury by falling oil or dirt from said mechanism.

A further object is to reduce the number of parts and to correspondingly reduce the expense of manufacture, while increasing the efficiency and convenience in operation of the machine.

My invention further relates to arrangements and combinations of parts which will be hereinafter described and more particularly pointed out in the appended claims.

A preferred form of the invention is shown in the drawings in which

Fig. 1 is a front elevation of certain parts of an oriental rug or carpet loom embodying my improvements;

Fig. 2 is an end elevation thereof, looking in the direction of the arrow 2 in Fig. 1;

Figs. 3, 4 and 5 are detail views showing successive positions of certain cutting members to be described; and

Fig. 6 is a front elevation of certain additional actuating mechanism.

Referring particularly to Figs. 1 and 2, I have indicated a knotting table 10 having supporting arms 11 at each end thereof, said arms being clamped at their upper ends to a rock shaft 12 supported in bearings 13 formed on brackets 14. The brackets are secured on a carriage 15 mounted on wheels or rollers 16 and supported on a fixed frame member 17. The carriage 15 is moved endwise a limited distance during the operation of the loom in order to insert successive yarn tufts along the

same transverse row in the fabric, all as fully set forth in the Renard patent above noted.

Intermediate supports 18 are provided, connecting the knotting table 10 to the cross shaft 12, said supports being merely to prevent sagging of the intermediate parts of the table, but not being relied upon for movement of the table. Links 20 are also pivotally connected at their lower ends to the rear portion of the table 10 and at their upper ends to bell cranks 21, actuated through a link 22 from a lever 23 (Fig. 6) having a roll 24 positioned in the groove 25 of a cam 26. As the cam rotates, the table is given a rocking movement for a purpose to be described.

Each of the supporting arms 11 is provided with a bracket 30 (Fig. 2) pivoted on the cross shaft 12 and having a cam roll 31 positioned in the groove 32 of a cam 33 mounted on a cam shaft 34. The shaft 34 is supported in bearings 35 in the brackets 14, and extends parallel to the rock shaft 12 and at the rear thereof. Each bracket 30 is provided with a slot 36 (Fig. 2) and is secured by a bolt 36' in adjusted angular relation to its supporting arm 11.

The cam shaft 34 and cams 33 move longitudinally with the carriage 15, and the shaft 34 is rotated through a bevel gear 37 keyed thereto but slidably thereon. The gear 37 may thus remain in fixed axial position while the shaft 34 moves longitudinally with the carriage 15.

I have indicated warp threads W passing through a reed 40 on a lay 41, and I have indicated the woven fabric F as being drawn down over a cloth roll 42. The pile yarns Y are mounted in a dividing head 43, fully shown and described in the Renard patent, and the yarns are selectively drawn therefrom in a direction parallel to the lay by grippers or pliers (not shown).

A series of knives 45 are mounted on the rear portion of the knotting table and the movement of the table is such that the knives 45 pass below and rearward of the pile yarns Y, as indicated in Fig. 3. The table 10 is then rocked by the cam 26, connected through the links 20, to bring the knives up under the pile yarns as indicated in Fig. 4. The knotting table is then swung rearward while at the same time the knives 45 are moved forward. This causes the parts to assume the position shown in Fig. 5, substantially with-

out lateral displacement of the pile yarns. The knives 45 are then given a forward cutting movement, severing each short length of pile yarn, which is thereafter twisted or knotted by the mechanism carried by the knotting table 10.

For a more detailed explanation of the operation of the knives 45 and other associated mechanism, reference is again made to the 10 Renard patent.

From the preceding description, it will be seen that I have provided direct and simple supporting and actuating mechanism for the knotting table, said mechanism being located 15 entirely at the ends of said table and at the rear of the supporting arms. By this construction I leave the front of the machine clear and free and I also avoid the possibility 20 of injury to the fabric by the dropping of oil or dirt from the table operating mechanism.

Having thus described my invention and the advantages thereof I do not wish to be limited to the details herein disclosed otherwise than as set forth in the claims, but what 25 I claim is:

1. In an oriental rug loom, a knotting table having yarn severing and yarn twisting mechanism mounted thereon, said yarn severing mechanism operating prior to the operation 30 of the yarn twisting mechanism, a rock shaft, a plurality of supporting arms depending from said rock shaft and to which said table is pivotally connected, a cam shaft rotatably mounted parallel to and at the rear 35 of said rock shaft, cams on said cam shaft, and operating connections between each cam and the associated supporting arm by which said table is oscillated.

2. In an oriental rug loom, a knotting table 40 having yarn severing and yarn twisting mechanism mounted thereon, said yarn severing mechanism operating prior to the operation of the yarn twisting mechanism, a rock shaft, a plurality of supporting arms de-

pending from said rock shaft and to which 45 said table is pivotally connected, a cam shaft rotatably mounted parallel to and at the rear of said rock shaft, cams on said shaft, and actuating connections from said cams to certain 50 of said supporting arms, said connections being positioned entirely at the ends of said knotting table and behind said supporting arms.

3. In an oriental rug loom, a knotting table 55 having yarn severing and yarn twisting mechanism mounted thereon, said yarn severing mechanism operating prior to the operation of the yarn twisting mechanism, a rock shaft, a plurality of supporting arms depending from said rock shaft and to which 60 said table is pivotally connected, a cam shaft rotatably mounted parallel to and at the rear of said rock shaft, cams on said cam shaft, and operating connections between said cams and the associated supporting arms by which 65 said table is oscillated, said connections including brackets pivoted on said rock shaft and each engaged by one of said cams, and means to secure each bracket to its associated supporting arm in adjusted angular relation thereto. 70

4. In an oriental rug loom, a knotting table having yarn severing and yarn twisting mechanism mounted thereon, said yarn severing mechanism operating prior to the operation of the yarn twisting mechanism, a rock shaft, 75 a plurality of supporting arms depending from said rock shaft and to which said table is pivotally connected, a cam shaft rotatably mounted parallel to and at the rear of said rock shaft, a cam at each end of said cam shaft so having a groove in its side face, and a cam roll mounted on a rearward projection from each end supporting arm and positioned in an associated cam groove for actuation thereby.

In testimony whereof I have hereunto affixed my signature. 85

MARIUS A. BAUER.
